CHANGEABLE EXHIBITOR

Carl Albert Loewenstein, Berlin, Germany, assignor to Ernst Gustav Preuss, South Lodge, St. John's Wood, England

Application October 28, 1937, Serial No. 171,410
In Germany May 28, 1937

6 Claims. (Cl. 40—65)

This invention relates to changeable exhibitors, and has for its object the provision of an exhibitor of that type which is compact, strong, durable and by which a relatively large number of pictorial or other exhibits may be accommodated and moved selectively into display positions.

Although the invention is adapted for use in the display of many classes of pictorial or other presentations, it is herein illustrated as embodying in an exhibitor particularly adapted for use in selectively displaying a plurality of map sections which collectively constitute a map of relatively large proportions.

In the drawings—

15 Fig. 1 is a view partly in face relation and partly in section of a changeable exhibitor embodying the present invention;

20 Fig. 2 is a view showing the device of Fig. 1 as it appears from the right thereof, but with portions of the housing broken away and with other portions of such housing shown in section;

25 Fig. 3 is a fragmental view similar to that of Fig. 1, but showing the device of that figure as viewed from the rear thereof;

30 Fig. 4 is an enlarged, transverse, sectional view taken on line 4—4 of Fig. 1;

Fig. 5 is a face view of the operating unit of Fig. 1, but removed from its housing and with its several secondary actuators devoid of map strips.

35 Fig. 6 is a view showing the operating unit of Fig. 5 as it appears from the right thereof;

Fig. 7 is a sectional view taken on line 7—7 of Fig. 5;

40 Fig. 8 is a diagrammatic view showing certain groups of map strips and illustrating a particular map-strip-relation.

Fig. 9 is a view showing the operating unit of Fig. 5 as it appears from either the top or the bottom thereof, and

45 Fig. 10 is a transverse, sectional view taken on line 10—10 of Fig. 5.

The particular device herein illustrated as embodying the present invention includes an operating unit 10 which is adapted to be carried within a receptacle-like housing 11.

Referring particularly to the operating unit 10, it will be observed that it includes a supporting frame 12. This supporting frame comprises a pair of side frame members 14 and a pair of end frame members 15. Each of the side frame members 14 includes a pair of guide strips 16 between which opposite ends of the end frame members 15 are suitably secured.

50 As to the end frame members 15, it will be observed that they are spaced a substantial dis-

tance from each other and serve in themselves to maintain the guide strips 16 of each side frame member 14 in spaced relation, thus providing a pair of guide slots 17—one for each of the side frame members. The guide slots 17 are adapted to accommodate opposite ends of a plurality of transversely disposed actuators 18 which are arranged in a parallel relation to each other and are adapted to be shifted longitudinally of the frame 12 to various positions intermediate the 5 end frame members 15, it being observed that the length of the guide slots 17 is such, with respect to the combined width of the several actuators 18, as to permit such actuators to be successively moved a distance corresponding to the width of 10 any given actuator.

Referring further to the end frame members 15, it will be observed that each of them terminates well short of the ends of the side frame members 14 except for their outwardly extending 20 leg-like extensions 20 which are disposed intermediate the guide strips 16 and terminate substantially flush with the ends thereof. Secured to opposite faces of the end frame members 15 are a pair of central guide strips 21 which are 25 disposed intermediate the side frame members 14 and between which the several actuators 18 are slidably accommodated.

For the sake of clarity in defining the structural and functional relation of the actuators 18 to their respectively associated and hereinafter identified parts, such actuators are designated 30 a, b, c, d and e. Referring to the actuators a to e inclusive, it will be observed that they are respectively connected, as by rivets 22, to pairs of secondary actuators a'—a', b'—b', c'—c', d'—d' and e'—e', which secondary actuators are arranged in a parallel relation to each other and are adapted to be moved longitudinally of the frame 12 in response to corresponding movement 35 of their respectively associated actuators a to e inclusive. As shown most clearly in Fig. 5, the secondary actuators a'—a', b'—b', c'—c', d'—d' and e'—e', are arranged in two groups, one group being located at one side of the longitudinal center of the frame 12 and the other group being 40 arranged at the other side of such center; and as shown most clearly in Figs. 4, 7, 9 and 10, each secondary actuator includes a pair of actuator strips 24 between which the actuators a to e inclusive are accommodated. As to the actuators 45 a to e inclusive, it will be observed that any one of them is slidable with relation to all secondary actuators a'—a' to e'—e' except that pair to which said one actuator is rigidly connected by 50 55

its associated rivets 22. As shown most clearly in Figs. 7 and 9, adjacent ends of the actuator strips 24 of each secondary actuator *a*' to *e*' are secured together through the medium of a tape-like binder 25.

Although the invention is adapted for use in the display of many classes of pictorial or other presentations, it is herein illustrated as embodied in an exhibitor particularly adapted for use in selectively displaying a plurality of map sections which collectively constitute a map of relatively large proportions. The map sections may be numbered—1, 2, 3, 4, etc., in order to enable one, through the aid of a suitable "key", to quickly 10 and selectively present any section in which he may be particularly interested at a given instant. For example, if one is interested in that section 15 of the United States of America which comprises the New England States and the "key" indicates that the New England section is identified by the numeral 1, the user of the device embodying the present invention may, without difficulty, selectively present map section No. 1 to the exclusion 20 of all other similar map sections regardless of whether they be few or many. In the present embodiment of the invention, provision is made for the displaying of twelve map sections—six at one side of the device and a corresponding number 25 at the other side thereof. In this connection, it will be observed that the actuators 18 are provided near their opposite ends with numerals 1 to 12 in association with arrows, which indicate the direction in which the respective actuators shall be moved in order to present the 30 various map sections.

As to the various map sections, each of them includes a plurality of (herein shown as ten—see Figs. 1 and 3) transversely disposed map strips MS, the map strips appearing as presented to view in Fig. 1 collectively representing map section No. 2 and those appearing in Fig. 3 representing map section No. 8. As to the map strips MS, it will be observed that each of them is provided with a pair of leg-like extensions 26, which, 40 in the case of the map strips 1' and 12' peculiar to map section No. 1, are attached to the side frame members 14, and which, in the case of the map strips 2' to 11' inclusive peculiar to map sections Nos. 2 to 11 inclusive, are connected in 45 an appropriate order to the secondary actuators *a*'—*a*' to *e*'—*e*' inclusive. Thus, it will be appreciated that by moving, for example, actuator *a* downwardly from its position shown in Fig. 5 to a position in close proximity to actuator *b*, 50 map section No. 1 will be presented at one side of the device, whereas map section No. 7 will be presented at the other side of the device. It is believed that the manner in which such presentation is effected may be better appreciated by referring to Fig. 8 which, although of a fragmentary nature, is sufficient to diagrammatically illustrate the map-strip-relation prevailing when map section No. 2 is presented. The lowermost group of map strips of Fig. 8 are those appearing 55 in Fig. 1 as located at the rear of the housing 11 within which the operating unit 10 is carried, and the uppermost group of map strips of Fig. 8 are those appearing in Fig. 1 as exposed to view at the upper end of said housing, whereas 60 the remaining two groups of map strips of Fig. 8 are illustrative of the map-strip-relation of all other intermediate groups of map strips when the device is conditioned as in Fig. 1. Referring further to Fig. 8, it will be observed that, due to 65 the position of actuator *a* in Fig. 1, map strips 70

2' overlie and obscure map strips 1'. The exposed map strips 2' collectively formulate map section No. 2, and, when moved downwardly in response to a similar movement of actuator *a*, are themselves obscured by the respective groups 5 of map strips behind which they are adapted to assume inactive positions. As the map strips 2' are moved downwardly, map strips 1' are exposed and so register as to formulate map section No. 1. It will, of course, be understood that while map strips 2' are maintained in exposed positions at one side of the device, map strips 8' (which collectively formulate map section No. 8) are exposed at the other side of the device; that upon moving actuator *a* downwardly, map strips 8' 10 are obscured, as described in connection with map strips 2', and that map strips 7' (which collectively formulate map section No. 7) are exposed as described in connection with map strips 1'. 15

It is believed in view of the foregoing description of the operation of the device (particular reference being had to actuator *a* and the map sections controlled thereby, namely, Nos. 2 and 7) that it is unnecessary to particularly describe 25 the manner in which the several actuators *b*, *c*, *d*, and *e* may be operated to selectively present the several map sections which they control (namely, map sections Nos. 3, 9; 4, 10; 5, 11; and 6, 12), other than to point out that any selected one of 30 these latter-named map sections may be presented to view by moving the actuator (bearing the identifying numeral corresponding to the number of the selected map section) in the direction of the arrow associated with said identifying 35 numeral.

As herein previously stated, the operating unit 10 is carried within the housing 11. This housing may be of any appropriate design, and is herein illustrated as including a pair of complementary 40 sections 27 and 28, the marginal wall 27' of the former of which is adapted to telescopically fit and be held within the marginal walls 28' of the latter. The sections 27 and 28 are provided, respectively, with windows 30 and 31 which are of 45 such dimensions that the map sections Nos. 1 to 6 inclusive may be presented to view at one side of the device whereas the map sections Nos. 7 to 12 inclusive may be presented to view at the other side of the device. The windows 30 and 31 are 50 equipped with sheets 32 and 34 of transparent material, such as "Celluloid", which are suitably connected to the window-boundary-margins of the sections 27 and 28, respectively, and serve as protective coverings for the operating unit 10 55 and particularly the several map strips MS forming elements of that unit. In order that the actuators 18 may be manipulated from without the housing 11, each of such actuators is of a length somewhat greater than the overall width of the 60 housing and the side marginal walls 27' and 28' of the sections 27 and 28 are so constructed as to slidably accommodate the outer or protruding ends of the several actuators.

Although only one form of the invention is 65 herein shown and described, it will be understood that various changes may be made and that the invention may be employed in the display of many classes of presentations other than maps without departing from the spirit of the invention or 70 the scope of the following claims.

What is claimed is:

1. In a changeable exhibitor; an operating unit comprising a frame, including side members having slots provided therein, said slots being aligned 75

- transversely of said frame and extending longitudinally of the same; a plurality of groups of presentation strips, the strips of the respective groups being collectively peculiar to different presentations, the strips of one group being fixed with relation to said frame, and the strips of the other groups being movable en group with relation to said fixed strips; and a plurality of actuators extending transversely of said frame in a parallel relation and slidably supported by said frame within said slots and individually connected to said groups of movable strips for effecting displacement of any selected group of movable strips with relation to the other groups of strips whereby any selected group of strips may be presented to view in a coordinated pictorial relation to the exclusion of the other groups of strips.
2. In a changeable exhibitor; an operating unit comprising a frame, including side members having slots provided therein, said slots being aligned transversely of said frame and extending longitudinally of the same; a plurality of groups of presentation strips, the strips of the respective groups being collectively peculiar to different presentations, the strips of one group being fixed with relation to said frame, and the strips of the other groups being movable en group with relation to said fixed strips; a plurality of actuators extending transversely of said frame in a parallel relation and slidably supported by said frame within said slots; and a plurality of secondary actuators disposed in a parallel relation to each other and extending longitudinally of said frame and secured respectively to the first-mentioned actuators and adapted to be moved thereby longitudinally of themselves, said secondary actuators being respectively connected to the movable groups of said strips for effecting displacement of any selected group of movable strips with relation to the other groups of strips whereby any selected group of strips may be presented to view in a coordinated pictorial relation to the exclusion of the other groups of strips.
3. In a changeable exhibitor; an operating unit comprising a frame, including end members, side members having slots provided therein, and center guide strips attached to opposite faces of said end members and spaced from each other; a plurality of groups of presentation strips, the strips of the respective groups being collectively peculiar to different presentations, the strips of one group being fixed with relation to said side members, and the strips of the other groups being movable en group with relation to said fixed strips; a plurality of actuators associated with said frame and slidably supported within said slots and the space afforded intermediate said center guide strips; and a plurality of secondary actuators disposed in a parallel relation to each other and extending longitudinally of said frame and secured respectively to the first-mentioned actuators and adapted to be moved thereby longitudinally of themselves, said secondary actuators being respectively connected to the movable groups of said strips for effecting displacement of any selected group of movable strips with relation to the other groups of strips whereby any selected group of strips may be presented to view in a coordinated pictorial relation to the exclusion of the other groups of strips.
4. In a changeable exhibitor, an operating unit comprising a frame, a plurality of groups of presentation strips, the strips of the respective groups being collectively peculiar to different presentations, a plurality of actuators slidably associated with said frame and cooperatively associated with said strips for effecting relative displacement of any selected group of strips with relation to the other groups of strips whereby any selected group of strips may be presented to view in a coordinated pictorial relation to the exclusion of the other groups of strips, and a housing adapted to receive said operating unit and including a pair of complementary sections provided respectively with windows through which different presentations may be observed and having side margins beyond which opposite ends of said actuators are adapted to project thereby to facilitate manual manipulation thereof.
5. In a changeable exhibitor; an operating unit comprising a frame, including side members having slots provided therein; a plurality of groups of presentation strips, the strips of the respective groups being collectively peculiar to different presentations, the strips of one group being fixed with relation to said frame, and the strips of the other groups being movable en group with relation to said fixed strips; a plurality of actuators slidably supported by said frame within said slots and individually connected to said groups of movable strips for effecting displacement of any selected group of movable strips with relation to the other groups of strips whereby any selected group of strips may be presented to view in a coordinated pictorial relation to the exclusion of the other groups of strips; and a housing adapted to receive said operating unit and including a pair of complementary sections provided respectively with windows through which different presentations may be observed and having side margins beyond which opposite ends of said actuators are adapted to project thereby to facilitate manual manipulation thereof.
6. In a changeable exhibitor; an operating unit comprising a frame, including end members, side members having slots provided therein, and center guide strips attached to opposite faces of said end members and spaced from each other; a plurality of groups of presentation strips, the strips of the respective groups being collectively peculiar to different presentations, the strips of one group being fixed with relation to said side members, and the strips of the other groups being movable en group with relation to said fixed strips; a plurality of actuators associated with said frame and slidably supported within said slots and the space afforded intermediate said center guide strips; a plurality of secondary actuators disposed in a parallel relation to each other and extending longitudinally of said frame and secured respectively to the first-mentioned actuators and adapted to be moved thereby longitudinally of themselves, said secondary actuators being respectively connected to the movable groups of said strips for effecting displacement of any selected group of movable strips with relation to the other groups of strips whereby any selected group of strips may be presented to view in a coordinated pictorial relation to the exclusion of the other groups of strips; and a housing adapted to receive said operating unit and including a pair of complementary sections provided respectively with windows through which different presentations may be observed and having side margins beyond which opposite ends of said actuators are adapted to project thereby to facilitate manual manipulation thereof.

CARL ALBERT LOEWENSTEIN.
